(57) **CLAIM**

The ornamental design for a camera mount, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a front perspective view of a hexagonal element of a camera mount of the present design, shown separately to show aspects of the design that may not be apparent in the other views;

FIG. 2 is a side view of the hexagonal element of the camera mount of FIG. 1;

FIG. 3 is a top view of the hexagonal element of the camera mount of FIG. 1;

FIG. 4 is a front view of the hexagonal element of the camera mount of FIG. 1;

FIG. 5 is a back view of the hexagonal element of the camera mount of FIG. 1;

FIG. 6 is a front perspective view of a hexagonal element of an alternate embodiment of a camera mount of the present design, shown separately to show aspects of the design that may not be apparent in the other views;

FIG. 7 is a side view of the alternate embodiment of the hexagonal element of the camera mount of FIG. 6;

FIG. 8 is a top view of the alternate embodiment of the hexagonal element of the camera mount of FIG. 6;

FIG. 9 is a front view of the alternate embodiment of the hexagonal element of the camera mount of FIG. 6;

FIG. 10 is a back view of the alternate embodiment of the hexagonal element of the camera mount of FIG. 6;

FIG. 11 is a front perspective view of a camera mount of the present design, consisting of multiple instances of the hexagonal element shown in FIGS. 1-5;

FIG. 12 is another front perspective view of the camera mount of FIG. 11;

FIG. 13 is a top view of the camera mount of FIG. 11;

FIG. 14 is a bottom view of the camera mount of FIG. 11;

FIG. 15 is a right-side view of the camera mount of FIG. 11;

FIG. 16 is a left-side view of the camera mount of FIG. 11;

(Continued)

FIG. 17 is a back view of the camera mount of FIG. 11; FIG. 18 is a front view of the camera mount of FIG. 11; FIG. 19 is a front perspective view of an alternate embodiment of a camera mount of the present design, consisting of multiple instances of the hexagonal element shown in FIGS. 6-10; FIG. 20 is another front perspective view of the alternate embodiment of the camera mount of FIG. 19; FIG. 21 is a top view of the alternate embodiment of the camera mount of FIG. 19; FIG. 22 is a bottom view of the alternate embodiment of the camera mount of FIG. 19; FIG. 23 is a right-side view of the alternate embodiment of the camera mount of FIG. 19; FIG. 24 is a left-side view of the alternate embodiment of the camera mount of FIG. 19; FIG. 25 is a back view of the alternate embodiment of the camera mount of FIG. 19; and, FIG. 26 is a front view of the alternate embodiment of the camera mount of FIG. 19. The broken lines shown in the drawings depict environmental subject matter only and form no part of the claimed design.
